UNITED STATES PATENT OFFICE.

SAMUEL G. SILBERMAN, OF PHILADELPHIA, PENNSYLVANIA.

DESIGN FOR AN AUTOMOBILE DOOR HANDLE.

Application filed December 2, 1924. Serial No. 11,557. Term of patent 14 years.

To all whom it may concern:

Be it known that I, SAMUEL G. SILBERMAN, a citizen of the United States, residing at Philadelphia, in the county of Philadelphia and State of Pennsylvania, have invented a new, original, and ornamental Design for an Automobile Door Handle, of which the following is a specification, reference being had to the accompanying drawings, forming part thereof.

In these drawings—

Fig. I is a side view of the handle, showing my new design and

Fig. II a top plan view of the same.

I claim:

The ornamental design for an automobile door handle, as shown.

SAMUEL G. SILBERMAN.
